JOURNAL LUBRICATORS

Llewellyn E. Hoyer, Wyckoff, and Edward R. Gorczyca, Mahwah, N.J., and John R. L. Santos, Baltimore, Md., assignors to American Brake Shoe Company, New York, N.Y., a corporation of Delaware

Filed May 1, 1956, Ser. No. 582,030

4 Claims. (Cl. 308—243)

This invention relates to journal lubricators.

Proper lubrication of journals, particularly journals running on partial bearings in a journal box of a railway car, is particularly troublesome in some instances, and it has been generally concluded that resort to waste packing in a railway journal box is responsible for many of the operational hazards such as hot boxes that have been encountered due to improper lubrication of the bearing.

The use of an absorbent, pad-like lubricator in a journal box below the journal has been proposed, and in this instance oil or like lubricant is fed by capillarity from a supply in the bottom of a journal box on to the journal. Such a pad may be in the form of oil-resistant, relatively resilient porous rubber such as synthetic open or closed cell neoprene foam rubber, and it has been found advantageous to encase a pad of this kind in a cover of wicking material which assures that the pad is protected against glazing over due to running of the journal on the pad. At the same time, the wicking characteristic of the cover assures a supply of lubricant absorbed in the pad to the journal. It is recognized that a journal lubricator of this kind may tend to be shifted to one side or the other of the journal box due to motion of the journal. This, of course, is a disadvantage, because the lubricator under such conditions is not centered in the bottom of the journal box where usually the lubricant is at its maximum depth, and moreover there is danger that the lubricator when shifted will be pinched between the journal and the bearing.

In a co-pending application, Serial No. 550,348, filed December 1, 1955, there is disclosed one kind of pad-type lubricator having a wicking cover modified in such a way as to substantially inhibit the foregoing tendency of the lubricator to be shifted laterally within the box, and this particular lubricator has other advantages fully described in the aforesaid application.

There are some extreme occurrences in freight service caused by sudden acceleration or deceleration in combination with lateral thrust, or even on curves in the road, where the journal exerts rather severe thrusts on the lubricator, and under the present invention we have found that a journal lubricator comprising a porous pad having a cover of high wicking characteristics can be prevented from following the motion of the journal under such severe conditions by stiffening opposed ends of the cover to afford in effect stiff end panels or sections adapted to engage abutments on the inner side walls of the journal box so as to limit the extent to which the lubricator can be shifted by the journal, and so to do is one of the primary objects of the invention. Specifically also, we have found that by disposing a pair of such pads within a sleeve-like cover, and by drawing together opposite faces of the cover intermediate the pads, enhanced lubricating characteristics are developed which assure effective absorption of the lubricant in the bottom of the journal box by the pads, and the accomplishment of this is a further object of the invention.

Ideally, the wicking cover for an absorbent lubricating

2

pad should have practically identical wicking characteristics both laterally and longitudinally to assure that the portion of the journal engaged by the cover has lubricant fed uniformly thereto, and a further object of the present invention is a lubricator having a cover with this desirable characteristic.

Another object of the present invention is to provide in a lubricator of the foregoing kind a positive acting lock or deterrent to shifting of the lubricator axially of the journal.

Other and further objects of the present invention will be apparent from the following description and claims and are illustrated in the accompanying drawings which, by way of illustration, show preferred embodiments of the present invention and the principles thereof and what we now consider to be the best mode in which we have contemplated applying these principles. Other embodiments of the invention embodying the same or equivalent principles may be used and structural changes may be made as desired by those skilled in the art without departing from the present invention and the purview of the appended claims.

In the drawings:

Fig. 1 is a perspective view of one form of lubricator constructed in accordance with the present invention;

Fig. 2 is a sectional view through a standard or AAR approved railway journal box showing a lubricator of the present invention installed therein to lubricate the car journal;

Fig. 3 is a fragmentary detail view showing an operational relation that may occur at an end of the lubricator;

Fig. 4 is a fragmentary sectional view similar to Fig. 2 showing an alternative journal box construction;

Figs. 5-5A, 6-6A, and 7-7A are fragmentary detail views showing alternative ways of stiffening ends of the lubricator;

Fig. 8 is a perspective view of the invention embodied in a lubricator having but a single porous pad;

Fig. 9 is a perspective view of a lubricator of the present invention having rigid extensions adapted to embrace the stop columns or like abutments in a journal box;

Fig. 10 is a partial sectional view of a standard journal box showing the lubrication of Fig. 9 installed therein; and

Figs. 11 and 12 show diagrammatically the preferred weave for the lubricator cover.

The present invention is illustrated in Fig. 1 of the drawings as embodied in a journal lubricator 20 constructed specifically for the lubrication of a journal running in a partial bearing of a railway car, and in Fig. 2 the lubricator 20 is shown operatively disposed between the bottom of the journal box JB and the journal J of the railway car. Disposed in the upper section of the journal box JB is a partial bearing B of conventional construction having a bearing face BF of bearing metal on which the journal runs, and the bearing is held in place in the journal box by the usual wedge W. The journal box JB is provided interiorly with opposed stop columns SC-1 and SC-2 that prevent axial shifting of the bearing B, this being in accordance with one form of standard journal box construction. Advantage is taken of this in accordance with the present invention as will be described herein below.

Under the present invention, the lubricator 20 comprises a one piece, sleeve-like or tubular cover 21 which is of a wicking material having substantially equal wicking rates both in a longitudinal and transverse direction, which is to say that the wicking rate or ability to pass liquid by capillarity is the same in the direction of the filling threads as it is in the direction of the warp threads.

The particular weave for the cover 21 which achieves this advantageous characteristic will be described herein below.

Disposed in spaced relation within the cover 21 are a pair of oil-resistant, relatively resilient porous pads 25A and 25B of rectangular block-like construction, Fig. 2, preferably of open cell neoprene sponge synthetic rubber adapted to absorb and retain relatively large quantities of lubricating oil. Thus, prior to installation, the lubricator 20 is drenched in oil and allowed to absorb to the full capacity of the pads 25A and 25B so that in operation the lubricator 20 not only operates on the relatively large amount of lubricant thus absorbed therein but also on the lubricant that is present in the bottom of the journal box approximately to a one and one-half inch level as indicated at L in Fig. 2.

As described in the aforesaid co-pending application, enlarged oil retaining passages 26 are formed inwardly of the opposed faces of the pads 25A and 25B. It will be observed in Fig. 2 that these passages 26 have dead ends terminating within the body of each pad. As is well known, there are many times when relative vertical motion occurs between the journal J and the journal box JB. When this takes place, the pads of the lubricator 20, 25A and 25B, are compressed in the journal box and oil in those passages 26 having openings at the lower faces of the pads will be placed under pressure, and oil in effect is pumped upwardly through the dead ends of the passages 26 as jets or sprays thereby furnishing the journal J with relatively large amounts of lubricant. Where the pads 25A and 25B are of open cell material, this takes place readily, and where the pads 25A and 25B are of closed cell type the dead ends of the passages 26 and the portions of the pad beyond are punctured or tapped to enable the foregoing pumping action to occur effectively.

Under one form of the present invention, the two pads 25A and 25B within the cover 21 are separated by drawing together and fastening as by a transverse stitch 21S, Fig. 1, the opposite faces of the cover 21 at the intermediate area 21A, Fig. 1, between the adjacent inner ends of the pads 25A and 25B. The intermediate panel or reduced transverse area 21A of the cover thus afforded enables the lubricator 20 to be easily folded upwardly at such mid-point stitched area so that symmetrical portions of the lubricator are in effective contact with opposed sides of the journal within the journal box as shown in Fig. 2, and at the same time the lubricator conforms readily to the rounded bottom of the journal box. Such inward folding of the cover 21 at the transverse center thereof inherently produces upper and lower inverted V-shaped channels 27 and 28, Fig. 2, separated by the intermediate panel 21A. The lower of these two channels, 27, in effect, forms an oil dome at the bottom of the journal box wherein lubricant L tends to be confined to feed the inner adjacent ends of the two pads 25A and 25B. Likewise, the upper of the two channels, 28, is effective also to insure a relatively uniform and concentrated feeding action of oil into the adjacent end portions of the pads 25A and 25B. In other words, the portion of the cover 21 at the bottom center portion of the box does not engage the box so as to confine oil only at the ends of the lubricator; rather, the cover at this portion is free of the journal box and hence, oil is able to flow uniformly through the cover 21 along the sections opposite the channels 27 and 28.

To facilitate arrangement of the lubricator 20 properly within the journal box, brass grommets 30 and 31 affording hook receiving elements at opposite ends of the intermediate panel 21A are crimped to the cover 21 at this section. The lubricator 20 is fully symmetrical end for end, side for side, and face for face as will be observed in Fig. 1. Accordingly, the lubricator has neither an obverse nor reverse side, so that it makes no difference as to the disposition of the grommets 30 and 31 during insertion of the lubricator 20 into the journal box, so long as the intermediate section 21A is parallel to the longitudinal

axis of the journal J. Accordingly, when the lubricator is in place in the journal box, a grommet 30 or 31, Fig. 2, is exposed at the front of the journal box to be conveniently hooked by a packing hook or the like, either to properly 5 orient the lubricator within the journal box or to extract the lubricator from the journal box. As will be appreciated from Fig. 2, the ends of the lubricator having the brass grommets 30 and 31 will be displaced well below the collar portions of the journal.

10 It is not essential in every instance that the cover of the lubricator 20 be stitched at the mid-point between the pads 25A and 25B. The primary advantage of this is to bring the opposed faces of the cover 21 together at the mid-area 21A so as to accelerate passage of oil from the oil reservoir or bottom portion of the cover 21 to the journal or upper portion of the cover 21. The resultant channels 27 and 28 serve additionally for reception and flushing of foreign matter from the surface of the lubricator thereby affording cleaner contact between the lubricator 15 and the journal. Thus, where effective contact with opposed sides of the journal and ready conformance to the geometry of the bottom of the journal box is of prime importance, the stitch 21S can be omitted as will be apparent from Fig. 1, and the grommets 30 and 31 alone used to separate the pads 25A and 25B and divide the lubricator 20 into symmetrical sections. This use of the grommets alone as dividers produces channels like 27 and 28, although not of the full depth of the channels 27 and 20 28 accompanied by stitching. Moreover, the grommets 25 in this instance are displaced below collar portions of the journal J.

30 It will be recognized from Fig. 2 that it is desirable that the lubricator 20 remain substantially in the position illustrated whereat the channels 27 and 28 tap the reservoir lubricant at the major depth thereof. This is especially true in those instances where the level of lubricant is tending toward a minimum. In accordance with the present invention, the desired centering of the lubricator is maintained by stiffening the opposed ends of the sleeve 21 in which the pads 25A and 25B are disposed. Several 35 different ways of accomplishing this can be resorted to as will now be described, and in each instance the stiffened ends of the sleeve or cover are flexibly united to the main body of the cover.

40 One method of stiffening the ends of the cover 21 is by plates 35 and 36, Fig. 1, of heavy duty fiberboard or the like, and these end plates are secured to opposed cover flaps or extensions 38 and 39 at each end of the cover 21. Brass retainer bolts 40 are passed through the extended 45 flap portions 38 and 39 of the cover 21 and registered openings in the end plates 35 and 36. Brass nuts 41, Fig. 3, are used on the ends of the bolts 40 opposite the heads to draw the plates 35 and 36 toward one another and to fasten together tightly the end portions 38 and 39 of the cover 21. Preferably, ends of the bolts 40 which extend 50 beyond the nuts are ground off. In this way, the end portions as 38 and 39 of the opposed faces of the cover 21 are stiffened.

55 It was mentioned that the stop columns SC-1 and SC-2 cooperate with the lubricator 20. Thus, as will be apparent in Fig. 2, any tendency for the lubricator 20 to follow the clockwise motion of the journal J so as to shift toward the left side of the journal box as viewed in this figure will be limited by the stiffened left-hand end of the pad 21 engaging the bottom of stop column SC-1. The 60 relation is preferably such that the stiffened ends of the lubricator are of sufficient dimension that in the event the shifting tendency of the lubricator 20 is sufficient to in effect cause the portion of the lubricator inwardly of the stiffened end to be pushed toward the stiffened end resulting in the condition shown in Fig. 3, the stiffened end of the lubricator will have its outer edge disposed in protective relation PR, Fig. 3, beyond the upper face 21U of the cover 21. This condition would prevail if the 65 lubricator 20 were to be pushed or shifted to such an

extent that the outer ends of the plates 35 and 36 are immediately adjacent the lower edge of the bearing B. However, the relation shown in Fig. 3 being established at this time, the lubricator cover is guarded against being pinched between or cut by the bearing and the journal.

Standard or approved journal boxes sometimes are equipped with so-called waste retainers that are adapted specifically to retain in place waste packing where used for lubricating the journal. These retainers are either cast integral with the journal box or alternatively take the form of angle irons welded in place. In Fig. 4, such retainers are illustrated at RL-1 and RL-2 in the welded angle iron form on opposite sides of the journal box, and these abutments can be used advantageously in the same capacity as the stop columns above described to limit creep or movement of the lubricator of the present invention in the manner described above.

It was mentioned that various alternatives may be used for stiffening the ends of the cover 21. Thus, there may be used, as shown in Figs. 5 and 5A, a channel-shaped sheet metal plate 45 fastened to the end flaps 38 and 39 of the cover to be stiffened by grommets 46, and in Figs. 6 and 6A pairs of fiberboard plates 51 and 52 corresponding to the end plates 35 and 36 mentioned above are fastened together by grommets 53. There are circumstances where either the metal or fiberboard plates may be advantageously substituted by heavy-duty webbing fastened as by stitching to the ends 38 and 39 of the cover.

In Figs. 7 and 7A, the cover 21 is stiffened at its end portions merely by a plurality of grommets 55 that are used directly to stiffen the projecting end portions 38 and 39 of the cover 21. In this connection it may be mentioned that other fastening means equivalent to such grommets may be used, but an advantage of grommets as 46, 53 and 55 is that these can be engaged by a packing hook to adjust the lubricator in or withdraw the lubricator from the journal box.

Another alternative that may be employed advantageously under certain circumstances is to immerse the projecting end portions of the cover 21 in oil resistant glue, sizing or the like serving to impregnate the interstices of the cover 21 with material that sets to a tough, hardened, impervious state. Desirably, staples can be used to supplement the stiff coating. In each instance, the stiffened ends of the lubricator as 20 constitute handles enabling insertion of the lubricator into the journal box to be accomplished with facility, and this is of particular advantage where the lubricator has been heavily loaded with lubricant prior to insertion.

In Fig. 8, a one-piece lubricator 60 is shown as comprising a sleeve cover 61 embodying a weave to be mentioned below, and in this instance a single pad such as 25A or 25B mentioned above is inserted in the cover 61. Attached to free end flaps as 62 and 63 at opposite ends of the cover 61 are pairs of stiffening plates 64 and 65, fastened together in this instance by pairs of grommets 66. The lubricator embodying but one pad insert can be used for lubricating rotating journals or the like under circumstances where the conditions are not so severe as to require use of the dual pad and center channel arrangement described above.

In addition to preventing travel of the lubricator laterally within the journal box due to rotary motion of the journal J, it is advantageous also to prevent axial movement of the lubricator, and in Figs. 9 and 10 a lubricator 70 is illustrated as embodying lock plates 71 and 72 of relatively rigid fiberboard material which serve the dual purpose of preventing lateral as well as axial shifting of the lubricator. The lubricator 70 preferably is generally of the form and construction described above in connection with the lubricator 20, and hence includes a sleeve-like cover 73, embodying a weave to be mentioned below, two oil absorbent pads as 25A and 25B described above inserted in the cover 73, and grommets 74 and 75 placed at the front and rear portions of the intermediate

section 73A of the cover which is stitched between the grommets 74 and 75 to draw the upper and lower faces of the cover together at this intermediate section and afford channels as 27 and 28 described above.

5 Several different forms of construction may be utilized in affording the plates 71 and 72, and in Figs. 9 and 10 this is achieved by disposing inner edge portions of the plates 71 and 72 between upper and lower relatively narrow facing plates 77 and 78. Staples 80 are pressed 10 through juxtaposed portions of the face plates 77 and 78 and the portion of the plate 71 or 72 that is disposed therebetween. Alternatively, a pair of symmetrically configured plates 71 and 72 can be fastened to the flap or extended end portions of the cover 73, and in this instance reinforcing plates as 77 and 78 are, of course, not necessary.

As shown in Fig. 10, the plates 71 and 72 are of a length to extend from the opposed ends of the lubricator cover 73 upwardly to and beyond the stop columns SC-1 20 and SC-2 in the journal box.

The outer end portions of the plates 71 and 72 are notched at 71N and 72N respectively, and this affords pairs of outwardly projecting ears 81-82 and 83-84 at either end of the notches 71N and 72N. The notches 25 71N and 72N correspond in size to the width of the stop columns SC-1 and SC-2 so that when the lubricator is disposed in the journal box, the ears 81-82 and 83-84 closely embrace the stop columns SC-1 and SC-2, thereby locking the lubricator 70 against substantial axial 30 shifting movement. Such axial locking of the lubricator prevents contact of the lubricator with either the end collar of the journal or the fillet on the journal at the dust guard seat, and therefore the possibility of the collar or the fillet of the journal causing wear on corresponding 35 portions of the lubricator 70 is overcome. In this connection, it commonly occurs that rotation of the collar of the journal against the front end of the bearing as B will in time create sharp edges on the collar which could have a damaging effect on the corresponding portion of the lubricator as 70 if thrust toward the rotating collar. The front and rear grommets 74 and 75 when applied to the transverse medial area of the cover of the lubricator as shown in Fig. 9, produce relatively stiff protuberances 40 respectively at the front and rear ends of such medial area, thereby stiffening the medial area of the cover at the front and rear ends thereof. This is also true of course of the embodiment of the invention shown in Fig. 1. The forward one of the grommets, 75, as viewed in Fig. 9, enables the cover to be hooked by a waste hook 45 inserted through the open front of the journal box, and the rearward one of the protuberances afforded by the grommet 74 is engageable with the rear wall of the journal box thereby serving further to limit axial rearward movement of the lubricator in the journal box, especially in the event that the ears as 82 and 84 at the 50 front of the lubricator as shown in Fig. 9 should be broken or somehow removed.

It will be appreciated, of course, that stop columns as SC-1 and SC-2 are of standard dimension, and hence the notches 71N and 72N will likewise be of such standard size. In the event that a lubricator 70 is to be disposed in a journal box having retainers as RL-1 and RL-2, Fig. 4, of variable length, the lubricator can be furnished with unnotched plates 71 and 72, and prior to installation the plates 71 and 72 can be marked to indicate the required size of the notch, and the portions of the plates 71 and 72 between such markings can then be removed to afford ears at the ends of the notches for engaging the ends of the retainer ribs.

70 It is preferred in most instances that the cover for the lubricator be of endless tubular form, since this eliminates the necessity of stitching together free ends of the woven material to afford the necessary sleeve-like cover. It will be appreciated that such endless construction of the cover is preferred for the foregoing reason but is not,

however, essential, and the cover 73 shown in Fig. 9, is one wherein the cover was woven as a sheet with the free edges thereof being brought together and stitched at 70S to afford the desired sleeve-like cover structure for retaining the oil absorbent pads.

Under the present invention, the cover for the lubricator in each instance is so woven as to have substantially the same wicking rate in both a lateral and longitudinal direction, since this assures uniform saturation of the cover with lubricant, and further assures that lubricant wicks through and along the cover in a uniform directional manner. The particular weave by which this is accomplished is illustrated in Figs. 11 and 12, and in Fig. 11 the manner in which the cover material is woven to afford the afore-mentioned continuous tube is illustrated as distinguished on the other hand from a woven sheet or web such as was used for the lubricator 70 in Fig. 9. However, regardless of whether the cover is woven as an endless tube or in web form subsequently to be stitched at the free edges, the arrangement of warp, filling, and binder threads is the same as will now be described.

The woven cover in the present instance comprises two plies of warp threads affording an outward or face ply 90, Fig. 11, and an inner or back ply 91, and each such ply comprises warp threads 92 which are interwoven in a plain weave with filling threads 93, there being a filling pick 93F for the face ply and an associated filling pick 93B for the back ply. The two plies are connected together by a binder thread 95, and the binder thread is plain woven with respect to the filling threads, alternately between the plies. Thus, the binder thread 85 passes over and under in an alternate fashion adjacent pairs of superimposed filling threads 93F and 93B. As to Fig. 11, the arrangement, as was mentioned, is one illustrating a section parallel to the warp threads on the loom, the upper two-ply portion of the cover being woven simultaneously with the lower two-ply portion of the cover to afford an endless tubular cover. When the material is taken off the loom, the material is severed into sleeves of predetermined length corresponding to the desired size of the lubricator.

Fig. 12 is a schematic generation showing the path of the filling thread. Thus, referring to Figs. 11 and 12, it will be noted that the filling pick 93-1 is first extended through the warp threads 92 in the upper face ply 90. A second pick 93-2 is then taken through the back ply in the lower set of warp threads 92. A third pick 93-3 is then taken through the warp threads in the upper back ply, and finally a fourth pick 93-4 is extended through the warp threads in the lower face ply. It will be observed that these picks are indicated in Fig. 11.

The filling thread 93 is next shifted forwardly for the next set of four picks 93-5, 93-6, 93-7, and 93-8, occurring in the sequence described in connection with the first four picks. After the last four picks, 93-5 through 93-8, the filling thread 93 is again shifted forwardly and the cycle of the back and forth picks alternately between the upper and lower sets of face and back ply warps is repeated as indicated in Fig. 12.

It will be seen from the foregoing that under the present invention, a journal lubricator is afforded which includes a wicking cover so woven as to have substantially equal wicking rates in all directions, and the ends of the cover are provided with stiffened sections adapted to engage abutments in the opposed side walls of the journal box so as to prevent or limit lateral shifting of the lubricator. Such stiffened sections may be further modified to embrace the opposed ends of such abutments to prevent or limit axial shifting of the lubricator. Where such extended stiffening sections as 71 and 72 are resorted to, Fig. 10, the length thereof is chosen in respect of the stop columns SC-1 and SC-2 so that the outer extremities of the stiffening panels extend upward be-

tween the bearing lugs BL and side walls of the journal box, thereby limiting movement of the lock plates 71 and 72 to this extent.

Advantageously, the lubricator comprises a pair of 5 porous lubricator pads disposed within the cover, and the face portions of the cover are drawn together between the adjacent ends of the pads thereby affording oil distributing channels and traps for enabling foreign matter to be carried away from the face portion of the cover that engages the journal. In this connection, it should be pointed out that lubricant flowing downward from side edges of the bearing lining, as it will when the journal rotates, will be trapped in pockets TC, Figs. 2, 4 and 10, at the ends of the lubricator on either side of the journal. Lubricant thus trapped wicks rapidly to the face of the lubricator cover and hence supplements the primary reservoir at the bottom of the journal box, and any excess will flow along the pockets TC parallel to the axis of the journal to return the main supply at the bottom of the box.

Moreover, the cover of the lubricator is resistant to glazing and hence is able effectively to transmit lubricant to the journal for sustained periods of operation and without overheating.

20 Thus, while we have illustrated and described the preferred embodiments of our invention, it is to be understood that these are capable of variation, and we therefore do not wish to be limited to the precise details set forth, but desire to avail ourselves of such changes and alterations as fall within the purview of the following claims.

We claim:

1. A fully reversible journal lubricator of the kind described adapted to be disposed in a journal box and comprising, a cover of wicking material having opposed faces either of which is adapted to engage the journal, porous pad-like inserts arranged within said cover in spaced relation, the opposed faces of the cover at an area between the pads being drawn together and fastened one to the other to enable the cover containing the inserts to be folded inwardly on itself at such area to embrace opposite sides of the journal, hook-receiving elements afforded in the cover and arranged so that one such element is accessible from the front of the journal box regardless of which face of the cover is uppermost in the journal box, and marginal portions of the cover at the opposed ends thereof being stiffened by rigid plates adapted to engage a related abutment in the journal box to limit lateral creep of the lubricator due to rotation of the journal, said plates having related abutments to limit axial shifting of the lubricator in the journal box.

2. A journal lubricator of the kind described adapted to be disposed in a journal box and comprising, a woven cover of wicking material, a porous pad-like insert disposed within said cover, and rigid panels extending outwardly of said cover at opposite ends thereof and each adapted to engage a related abutment in the journal box to limit lateral creep of the lubricator due to rotation of the journal, said panels including means at the outer edges thereof adapted to embrace ends of such related abutments to prevent axial shifting of the lubricator within the journal box, said woven cover having substantially equal wicking rates in both lateral and longitudinal directions and to this end consisting of two plies of plain woven warp and filling threads with said plies being connected by binder threads plain woven with the filling threads alternately between the two plies.

3. A journal lubricator of the kind described adapted to be disposed in a journal box and comprising, a cover of wicking material having opposed faces, porous pad-like inserts arranged within said cover in spaced relation, the opposed faces of the cover at a medial area between the pads being transversely drawn together and fastened one to the other to enable the cover containing the inserts to be folded inwardly on itself at such area to embrace

opposite sides of the journal, hook-receiving eyelets of rigid material afforded in the cover and arranged so that one such element is disposed adjacent each end of said medial area of the cover to produce relatively stiff portions of the cover at the ends of said medial area, the element of rigid material at one end of said medial area enabling the lubricator to be hooked from the front of the journal box and the other element of rigid material and its related stiff portion serving to limit axial movement of the lubricator in a rearward direction when the lubricator is installed in the journal box, and marginal portions of the cover at the opposed ends thereof being stiffened by rigid plates each adapted to engage a related abutment in the journal box to limit lateral creep of the lubricator due to rotation of the journal, said plates having related abutments engageable with abutments in the journal box to limit axial forward shifting of the lubricator installed in the journal box.

4. A journal lubricator of the kind described adapted to be disposed in a journal box and comprising, a cover 20 of flexible wicking material, a porous oil-absorbent pad-like insert disposed within said cover, and panels of

5 material more rigid than the cover joined to flexible parts of the cover and extending outwardly of said cover at opposite ends thereof and each adapted to engage a related abutment in the journal box to limit lateral creep of the lubricator due to rotation of the journal, said panels additionally cooperating with the cover at the ends of the lubricator to afford traps for lubricant, said panels including means at the outer edges thereof adapted to embrace ends of such related abutments to prevent axial shifting of the lubricator within the journal box.
